(57) **CLAIM**

The ornamental design for a [a portion of] recoil cover for an internal combustion engine, as shown and described.

DESCRIPTION

Term notice: more than one reissue application has been filed for the reissue of U.S. Pat. No. Des. 549,241. The Reissue Application being filed herewith and Reissue application No. 29/316,068 are all divisional reissues of U.S. Pat. No. Des. 549,241.

FIG. 1 is a perspective view of a [portion of a] recoil cover for an internal combustion engine according to [an] a first embodiment of the present design;

FIG. 2 is a front elevation view of [the portion of] a recoil cover for an internal combustion engine shown in FIG. 1;

FIG. 3 is a top plan view of [the portion of] a recoil cover for an internal combustion engine shown in FIG. 1;

FIG. 4 is a bottom plan view of [the portion of] a recoil cover for an internal combustion engine shown in FIG. 1;

FIG. 5 is a right side elevation view of [the portion of] a recoil cover for an internal combustion engine shown in FIG. 1; and,

FIG. 6 is a left side elevation view of [the portion of] a recoil cover for an internal combustion engine shown in FIG. 1.

FIG. 7 is a perspective view of a recoil cover for an internal combustion engine according to a second embodiment of the present design;

FIG. 8 is a front elevation view of a recoil cover for an internal combustion engine shown in FIG. 7;

FIG. 9 is a top plan view of a recoil cover for an internal combustion engine shown in FIG. 7;

FIG. 10 is a bottom plan view of a recoil cover for an internal combustion engine shown in FIG. 7;

FIG. 11 is a right side elevation view of a recoil cover for an internal combustion engine shown in FIG. 7; and,

FIG. 12 is a left side elevation view of a recoil cover for an internal combustion engine shown in FIG. 7.

The broken lines shown in FIGS. [1-6] 1-12 are for illustrative purposes only and form no part of the claimed design.

1 Claim, 8 Drawing Sheets

Matter enclosed in heavy brackets [ ] appears in the original patent but forms no part of this reissue; matter printed in italics indicates the additions made by reissue.
